CLAIM

I claim the ornamental design for a corrective slipper, as shown and described.

DESCRIPTION

FIG. 1 is a perspective view of a corrective slipper showing my new design

FIG. 2 is a front view thereof;

FIG. 3 is a back view thereof;

FIG. 4 is a right side elevational view thereof;

FIG. 5 is a left side elevational view thereof;

FIG. 6 is a top view thereof; and,

FIG. 7 is a bottom view thereof.

The broken lines in the drawings represent portions of the corrective slipper that form no part of the claim.
